UNITED STATES PATENT OFFICE

99,264

DESIGN FOR A COMBINED VANITY CASE AND SMOKER'S RECEPTACLE OR THE LIKE

William F. Bowen, North Attleboro, Mass., assignor to Evans Case Company, a corporation
of Massachusetts

Application February 27, 1936, Serial No. 61,390

Term of patent 3½ years

To all whom it may concern:

Be it known that I, William F. Bowen, a citizen of the United States, residing at North Attleboro, county of Bristol, and State of Massachusetts,
have invented a new, original, and ornamental
Design for a Combined Vanity Case and Smoker's Receptacle or the Like, of which the following is a specification, reference being had to the accompanying drawing forming a part thereof.

In the accompanying drawing Fig. 1 is a perspective view of a combined vanity case and smoker's receptacle or the like showing my new design in open position. Fig. 2 is a perspective view thereof in closed position.

I claim:

The ornamental design for a combined vanity
case and smoker's receptacle or the like as shown.

WILLIAM F. BOWEN.
